GEAR PUMP

Walter C. Trautman, Chicago, Ill., assignor to Hupp Corporation, Cleveland, Ohio, a corporation of Virginia
Filed Jan. 22, 1958, Ser. No. 710,532
25 Claims. (Cl. 103—126)

This invention relates to gear pumps and more particularly to self-compensating gear-tooth pumps providing optimum clearance between relatively moving surfaces of pumping components.

Gear tooth pumps of previously known conventional construction consists of a combination of gears, casings and end plates, and the production of, and structural cooperation between, these components in the combination must be very closely controlled as a necessary and vital factor for satisfactory pump operation. In the simplest form of conventional gear tooth pumps, the casing and gears have relatively minute critical fixed clearances between gear peripheries and surrounding casing walls and between gear tooth side faces and the casing end plates and depend upon these relatively minute clearances for the pumping seals. As a consequence the pumps have large, relatively moving areas separated by such relatively minute clearances which usually results in considerable friction losses, leakage losses and hence in low mechanical efficiency.

Possibly the greatest limiting factor on the output pressure capacity of gear tooth pumps is the high load imposed on the gear shaft bearings by large unbalanced hydraulic pressures between outlet and inlet sides. In a conventional gear tooth pump, the inlet portion of the combination pump structure encompasses only a small extent of the gear peripheries and the area of casing periphery between the high pressure outlet side of the meshing gears and the low pressure inlet side of the gears is subject to varying magnitudes of outlet pressure. Because of the small critical clearances between gears and casing the pressure of fluid in those clearance spaces decreases in a progressive manner around the peripheries of the gears from the pump outlet to a position closely adjacent to the inlet portion of the gear peripheries. Because there is a small leakage through the peripheral clearance space, the fluid seal thus obtained cannot be absolute and this factor accounts for a pressure gradient around the gears. Considerable hydraulic pressure difference is thus applied against a major percentage of the gear peripheries resulting in a correspondingly high bearing load on the gear shaft bearings. A further disadvantage directly related to the gradient nature of this high pressure loading on the two gears in a conventional pump is that the pressure forces on each gear approach a condition approximating a balanced couple about the gear axis which makes such a pump mechanism highly inefficient and even inoperative if it is desired to be used as a motor.

As discussed above, the basic principle of operation of simple gear tooth pumps requires close control of the critical gear to casing clearance, and high bearing loads are inherent. These two factors contribute to cumulative rapid self-destruction of such pumps because even a minute gear shaft bearing wear will enable an increase in gear periphery clearance adjacent the gear periphery portions subject to outlet pressure. This increase multiplies bearing loads because of increased magnitudes in the pressure gradient along the critical clearance peripheral seal area and in turn causes faster bearing wear. As this rapid self-destruction progresses and gear teeth eventually hit and wear directly on the peripheral casing wall adjacent the inlet. This action can "freeze" the pump gears or further increase peripheral clearances

2

closer to the outlet. At this stage the pump becomes useless.

Previously known gear-tooth pumps require at least some portion of casing structure as a requisite part of the pumping mechanism seal, i.e. there must be some type of direct relative cooperation between an enclosing casing and the pumping gears to provide the required pumping and high pressure sealing action. A resulting effect of such structure is to subject the casing to high hydraulic pressures over a large portion of its interior, particularly on areas of the casing end plates. Consequently the end plates must be of heavy, thick-walled construction and the bolts, or the like, which connect the end plates to the casing must be of sufficient strength to withstand the developed forces. This requirement results in a high unit weight with a proportionate amount of material for construction. Reduction of this high weight and the use of less material are highly advantageous economical production and service features both of which are realized by this invention as will become apparent.

Accordingly, a primary object of this invention resides in the provision of a novel gear-tooth pump with self-compensating pumping mechanism supported in a casing structure which serves primarily as support structure for the pumping mechanism, and hence can be produced without the necessity of machining critical pumping surface dimensions.

A further object resides in the provision of a novel gear-tooth pump in which the pump gears and the casing are formed with optimum non-critical clearances and a pressure discharge assembly cooperates with a minimum extent of the gears adjacent the discharge side of intermeshed teeth whereby a major portion of the pump gear teeth are in contact with and directly receptive to the incoming fluid at the pump inlet, enabling the pump to be rotated at very high operational speeds and still accomplishing complete filling of the pump gear teeth before they move into pumping cooperation with the discharge assembly.

A still further object is to provide a self-compensating gear pump with an independent pumping assembly incorporating a pressure actuated gear tooth sealing member in combination with two independent gear side surface sealing members, all of said gear sealing members being urged into sealing engagement with the gears by hydraulic pressure equal to the pump discharge pressure at the meshing gear teeth output zone.

Another object resides in the provision of a novel gear tooth pump which has a casing type support for intermeshing pumping gears with non-critical clearances between the casing support structure and the gear end faces and peripheries, a thrust block engaging a minimum portion of the gear peripheries and two seal plates overlapping the gear end faces and the thrust block and sealingly biased between the casing wall into overlapped engagement with the gear end faces and the thrust block.

A related further object is to provide the seal plates, which sealingly engage portions of the side faces of the gear teeth and the thrust block and seal a space between the thrust block and intermeshed gear teeth in fluid communication with the pressure discharge side of the pump gears, with structure disposed between each seal plate and the casing to resiliently maintain the seal plate against the gears and thrust block.

A still further object resides in the provision of a novel self-compensating gear tooth pump including a support structure which journals the pumping gears in meshed relation, a thrust block contoured to fit a portion of the peripheries of both pumping gears having a thickness equal to the thickness of the pumping gears and having a discharge passage extending through the thrust block between the inner and outer pressure faces of the

block, the thrust block being maintained by a biasing force in sealing engagement with the gears. In conjunction with this object, a further object resides in the provision of a pressure area on the outlet side of the thrust block pressure passage of sufficiently greater dimension than the effective area of the thrust block pressure face and subjected to outlet pressure to provide a controlled biasing force on the thrust block.

Another object resides in a novel self-compensated gear tooth pump, as in the preceding object, which includes two seal plates overlapping the sides of said thrust block and the end faces of the teeth intermeshed gears adjacent their discharge to completely cover the pressure discharge space between the intermeshed gears and said thrust block, and resilient seal rings cooperate between the seal plates and the support structure to bias the seal plates toward engagement with the thrust block and pumping gears. In relation to this object, a further object resides in the novel provision for passage of fluid under pressure to a pressure area on said seal plate defined by the sealing ring so output pump pressure can be utilized to bias the seal plates toward the thrust block and pumping gears and the biasing force will be automatically compensated for changes in pump output pressures.

Still another object resides in providing a gear tooth pump with a novel, full floating, discharge zone, sealing assembly which includes a thrust block unit consisting of two halves subjected to a fluid pressure differential biasing force tending to maintain the halves in fluid film sealed engagement with the gear teeth and in direct sealed engagement with the pump body.

Yet another object resides in providing a gear tooth pump with a novel, full floating, discharge zone, sealing assembly which includes a thrust block unit made of flexible material and provided with an integral, block to casing, annular pressure sealing lip and tapered wall portions subjected to a differential biasing force resulting in wall deflection toward a discharge pressure controlled fluid film sealing cooperation with the pumping gear peripheries.

It is a still further related object to provide the seal plates with an orifice type fluid communication to the pump pressure space and to provide a controlled fluid outlet from the seal plates sealed area selectively operable to relieve fluid pressure from within the seal plate sealed areas thus enabling the seal plates to be biased by pump discharge pressure out of operative engagement with the thrust block and pumping gears to cause immediate cessation of pumping output.

Further novel features and other objects of this invention will become apparent from the following detailed description, discussion and the appended claims taken in conjunction with the accompanying drawings showing preferred structures and embodiments in which:

FIGURE 19 is a side elevation of still another pump in accord with this invention having a third alternate form of floating pressure seal assembly utilizing a combination thrust block and area seal; and

FIGURE 20 is a detail section view taken on line 20—20 of FIGURE 19 illustrating the shape of the thrust block.

All of the figures, with the exception of FIGURES 5 and 6, refer to inventive features and concepts of this invention as applied to various modifications of self-compensating pumps. FIGURES 5 and 6 represent a conventional, prior art, fixed clearance, gear tooth pump and are included in this disclosure as an aid in explaining the various fluid forces and the manner of structural cooperation between pump components in such prior art pumps which is considered detrimental to pump life under extensive high pressure service, thus affording a background understanding of the problems preceding the present invention and the improvement it contributes.

With reference to FIGURES 5 and 6, the primary components of a fixed clearance pump 20, in simplified form, are the casing 22 which includes recesses 24 and 26 receiving a pair of intermeshing spur gears 28 and 30, an inlet passage 32 and an outlet passage 34. The casing side surfaces 36 and 38, particularly immediately adjacent the periphery of the gear recesses 24 and 26, are of planar shape and disposed parallel to each other. Gears 28 and 30 can be made integral with their shafts 40 and 42 or separable and non-rotatably splined or keyed to the shaft. One of the shafts (not shown) extends at one of its ends a greater distance than the other shafts and has formed on that end some means for enabling a drive connection. As such a drive connection forms no part of the discussion relative to the pumping operation of conventional fixed clearance gear pumps there is no need for illustration.

Two end plates 44 and 46 are secured to opposite sides of casing 22 by bolts 48 threaded into the casing 22. Both of end plates 44 and 46 include a flat planar inner surface, 50 and 52 respectively. When the end plates 44 and 46 are secured to casing 22, a confined pumping

chamber is formed with the aforementioned recesses 24 and 26, the inlet 32 and the outlet 34. Boss portions 54 and 56 on respective end plates 44 and 46 include bores 58 for journaling the shafts 40 and 42 of the spur gears. The bores 58 in one of the end plates 44 are both blind bores whereas only one of the bores 60 in end plate 46 is a blind bore, the other bore in end plate 46 (not shown) being a through bore and including a suitable shaft seal to create a fluid seal around the projected drive connection end of gear shaft 40.

Typical radial and axial clearances required between the gears 28 and 30, the casing 22 and the end plates 44 and 46 of such a fixed clearance gear tooth pump are illustrated to an exaggerated extent for clarity. Actually the clearance between the gear periphery and adjacent wall of the casing is somewhere in the order of 0.003 to 0.004 inch and the axial clearance between the side face of the gear and matching inner face of the end plates 44 and 46 is in the order of 0.0005 to 0.0010 inch.

In let fluid entering through casing inlet 32 contacts the intermeshed gears in the small triangular space between the intermeshed gears and casing inner wall boundaries A and A seen in FIGURE 5. In this relatively small inlet chamber, the hollow spaces between each gear tooth must become filled with fluid as the teeth progress by rotation into sealing engagement with the circumferential inner wall of the casing recesses. The aforementioned small critical clearance must exist between the gears and the casing from boundary lines A around to the outlet space on the opposite sides of the intermeshing gears which space is in fluid communication with casing outlet 34.

The radial clearance between gears and casing although very minute is still a clearance and therefore can pass a considerable volume of fluid from the pressure side to the inlet side. Because of the minute clearance there is a resultant boundary layer friction between the layer of fluid in the clearance, the casing surface and the gear teeth end faces which, because it extends a major portion of the peripheral extent of the gears, results in an effective although not an absolute fluid seal. This is a progressive seal resulting in a pressure gradient developed from a maximum at the discharge area back to the points A adjacent the inlet port. In FIGURE 5 this pressure gradient is illustrated by the phantom lines B and the variation in pressures are indicated by the double headed, radial directed arrows placed within the pressure gradient diagram. The large arrows C represent the direction of resultant force acting on the gear shaft bearings as a result of the hydraulic pressure gradient.

Because the hydraulic pressure forces, even though reduced at locations near the inlet, exist substantially entirely around the periphery of the gears, the moment couple about the axis of each gear is relatively small considering the magnitude of pressure at the outlet port. It is this factor that makes such a fixed clearance gear type pump inefficient and in some respects inoperable as a fluid motor. Furthermore it can be seen that because of the large extent of the gear periphery which is subjected to the hydraulic pressure gradient that a high unbalanced force is created on the gear bearings which will tend to increase wear and shorten the bearing life which in turn cumulatively destroys the closely critical minute clearances surrounding the gear teeth and upon which depends the peripheral fluid sealing action for relatively efficient pump operation.

Still referring to FIGURES 5 and 6, it can readily be shown that at least 22 critical dimensions are present and must be considered during production of a fixed clearance, gear type pump. To properly position the end plates 44 and 46 on casing 22, dowel pins are accurately located in each end plate and match with corresponding dowel holes 62 and 64 in the matched surfaces of the casing 22. Each of end plates 44 and 46 has at least seven critical dimensions which are listed below accom-

panied by a representative critical tolerance applicable to a gear pump approximately the size illustrated in the drawings.

5 (1) The dowel pin location hole to the shaft bearing axis of one shaft bore 58 (.0005 inch).

(2) Axis of shaft bearing bore to the axis of the adjacent shaft bearing bore (.0005 inch).

(3) The axis of the adjacent shaft bearing bore to the opposite dowel pin location hole (.0005 inch).

10 (4) The first shaft bearing bore diameter (.0005).

(5) The second shaft bearing bore diameter (.0005).

(6) Offset (the side tolerance) of shaft bearing axis to the adjacent dowel pin axis (.001).

15 (7) Offset (side tolerance) of the other shaft bearing bore diameter to the opposite dowel pin axis (.001).

Note.—Since each end plate has the same critical dimensions, the two end plates in conjunction require at least 14 critical dimensions.

The critical dimensions of casing 22 are:

20 (1) The dowel pin locating hole axis to the center of the adjacent gear cavity (.0005 inch).

(2) The center of one gear cavity to the center of the adjacent gear cavity (.0006 inch).

(3) The dimension from the center of the second gear

25 cavity to the center of the second dowel pin (.0006 inch).

(4) The radius of one gear cavity (.0005 inch).

(5) The radius of the other gear cavity (.0005 inch).

(6) The offset (side tolerance) from gear cavity center to the center of the adjacent dowel pin hole (.001 inch).

30 (7) The offset (side tolerance) of the other gear cavity center to the axis of the adjacent dowel pin hole (.001 inch).

(8) The thickness of the gear casing which must be machined (.001).

35 The foregoing dimensions do not include any dimensions of the gear perimeters, thicknesses and shaft diameters which occur in all gear tooth type pumps. The tolerances listed above are total allowances and not plus and minus tolerances. They have been taken from a typical, commercial, fixed clearance gear tooth pump and illustrate the degree of precision required in this type of a pump.

40 The criticality of end plate dimensions numbers 6 and 7 above and the casing dimensions number 1 through 7 above have been eliminated by the present invention, as will be more fully described hereinafter, thereby reducing the above twenty-two critical dimensions in casing and end plates to eleven and constituting a major saving in production and inspection time.

45 Returning to FIGURES 1, 2 and 3, an exemplary embodiment of a gear pump 80 according to the present invention is illustrated. FIGURE 9 is a vertical cross-section showing further details of inner components while FIGURE 4 is a somewhat schematic perspective view which illustrates basic components of a pump incorporating the inventive concepts of this invention.

50 The major components of pump 80, FIGURE 1, are pump gears 82 and 84, a thrust block 86, seal plates 55 88 and 90, an annular thrust block seal 92 and upper and lower seal plate resilient seals 94 and 96. These eight components are assembled in a relatively loose abutting relationship within a support casing 98 which surrounds the gears with relatively large non-critical clearances. End plates 102 and 104 have bores 106 and 108 which receive bearing sleeves 110 and 112 for rotatably journaling gear shafts 114 and 116. One of the bores extends through its end plate and permits the projected end of one gear shaft to extend to the exterior of the gear support structure, for example, as shown in FIGURE 13. Surrounding this extended portion of one of the shafts is a seal such as the O-ring 118 (FIGURE 13) to prevent fluid leakage between the shaft and the end plate bore. Any appropriate seal may be utilized at this position, and it is noted that such seal

is not subjected to the high outlet pressure of the pump. Each gear 82 and 84 may be formed integral with or keyed to its associated shaft in the manner illustrated in FIGURE 9. The form of gear teeth used in conjunction with this invention can be any of the known types, two examples being involute or elliptical gear tooth forms such as represented in FIGURES 7 and 8 or the elliptical Davis type gear tooth described in U.S. Patent No. 2,261,143 and represented by the helical gears shown in FIGURE 4. Preferably the Davis type gear tooth is desired although the inherent drive weakness of the elliptical form of gear tooth will necessitate the use of helically disposed teeth. When using such teeth with the present invention the lead from one end face of one tooth to the opposite end face of the same tooth is at least equal to the distance from one tooth to the next tooth.

In FIGURE 4, only the primary components of the present pump are illustrated, these being the two gears 82 and 84, the thrust block 86 and the seal plates 88 and 90. The three resilient seal devices are omitted in this perspective view and the support structure for such components is represented by a circular casing 98 which also provides support for the bearings 110. FIGURES 4 and 8 serve to illustrate that no external gear casing is required to enable pumping operation of this type of gear pump. The wide clearance between the gear peripheries and the supporting casing enables inlet fluid to surround and fill the spaces between gear teeth along a major portion of both gears, and minimizes the occurrence of cavitation upon high speed rotation of the gears in a conventional pump due to the maximum limits of time and force available to propel the incoming liquid into the gear-tooth cavity, as the teeth move through the inlet chamber.

The force (pressure) is determined largely by the available suction pressure (29.92 inches Hg max.) and usually not over 20 inches in actual practice.

The time is determined by the rotary speed of the pump and is the time which it takes one tooth-cavity to cross the inlet port.

Since all hydraulic fluids are viscous it follows that; for a given viscosity of liquid and with the force available limited by physical laws, there is a maximum time element which can be tolerated to insure complete filling (i.e. non-cavitation) of the gear-tooth cavity.

In a conventional pump the arcuate distance (and therefore time) during which filling can take place is about 60 degrees of shaft rotation. In the pump of this invention this arcuate distance is somewhere in the vicinity of 200 degrees or more.

The thrust block 86 has a width (FIGURE 2) which must be exactly the same as the side face width of the pump gears 82 and 84. This dimension is critical and must be accurately maintained. Thrust block 86 is formed to coat with the teeth end faces of both gears 82 and 84 immediately adjacent the discharge space where the two gears intermesh. Two arcuate surfaces 120 and 122 at opposite ends of the pressure face of the thrust block 86 are accurately formed to the same radius as the outside or addendum circle of the pump gears 82 and 84. A pressure face 124 on thrust block 86 (FIGURE 9) is provided between arcuate surfaces 120 and 122 facing the meshing position of gears 82 and 84 and, with the gears, forms a pressure discharge zone 126 which has an essentially triangular cross-sectional shape. The length of arcuate surfaces 120 and 122 (see FIGURE 7) is such as to always engage the teeth lands along the full extent of at least one circular-pitch with straight teeth, and at least two circular-patch with teeth of helical formation where the distance from one side to the other of a single tooth is equal to the circular pitch distance between two gear teeth. FIGURE 7 illustrates the arcuate surface 120 of slightly greater length than is necessary for the aforementioned straight teeth of involute form.

Some means must be provided for maintaining the arcuate surfaces 120 and 122 of thrust block 86 in close, approximately engaged proximity with the peripheries of the pump gears 82 and 84 and it is preferred that this force be accurately controlled, for reasons which will become apparent hereinafter.

As will be apparent from the structural arrangement disclosed in FIGURES 1, 2 and 9, the rear face 128 of thrust block 86 will be subject to fluid under discharge pressure which flows from the front face 124 through a passage 129 in thrust block 86 and, by control of the areas of portions of arcuate surfaces 120 and 122 and front face 124 and of rear face 128 which are subjected to discharge pressures, a differential pressure will be realized on the thrust block 86 which will tend to force it toward the gear peripheries with a pressure of desired magnitude relative to the magnitude of output pressure.

Seal plates 88 and 90, best shown in FIGURES 1, 2 and 3, are illustrated as having a contour permitting the seal plate to contact side areas of the gears 82 and 84 within the root circles of the teeth, overlap the dead center position of intermeshed gear teeth, and engage a major portion of the side faces 130 and 132 of thrust block 86 providing a secondary wear-plate function. The contacting surfaces of seal plates 88 and 90 are machined smooth to closely cooperate with the coextensive side faces of the gears and of the thrust block. Each seal plate must overlie the point of gear meshing which is indicated as point G in FIGURE 1. It will also overlie the extreme ends H of the arcuate surfaces of thrust block 86. It can overlie the full area of the thrust block and extend past the thrust block area exposed to the annular seal 92. A pressure equalizing passage 134 extends through each seal plate to permit fluid communication of pump discharge pressure from the inner to outer side of the seal plate and enables such discharge pressure to act on the outer face of the seal plates 88 and 90. Although the seal plates 88 and 90 are illustrated in FIGURES 1, 2 and 3 as overlying a portion of the support casing 98 immediately adjacent the casing discharge outlet 136, such feature is not necessary although if such structure is not used, the annular seal 92 must provide a seal between the thrust block 86, the casing support structure 98 and the end plates 102 and 104, e.g. as shown in FIGURE 13.

The annular seal 92, preferably made of resilient material such as an oil-resistant synthetic rubber (e.g. "Buna N") or a corrosive resistant synthetic (e.g. "Teflon"), provides a fluid seal between the thrust block 86, seal plates 88 and 90 and casing structure 98, as above described, and furthermore provides a resilient biasing force which tends to maintain thrust block 86 against the gear peripheries when pump 80 is not delivering fluid under pressure. Fluid under pressure acting on the internal groove 137 of annular seal 92 tends to expand seal 92, aiding its seal function and exerting a force on the thrust block 86.

An alternative possible seal construction which does not require the annular seal 92 is shown in FIGURE 11 where an integral spigot projection 140, provided on thrust block 86', extends into a cylindrical bore 142 co-extensive with the support structure outlet 136'. Suitable sealing means such as the O-ring 144 disposed in an annular groove in spigot member 140 provides a fluid seal between the spigot and casing 92' preventing high pressure fluid from flowing back to and around the rear face of the thrust block and interior of the casing structure. The relationships of the cross-sectional area of spigot member 140 and the combined effective pressure area of flat surface 124' and varying pressure areas existing on the arcuate surfaces 120' and 122' can be designed to give a differential pressure having values of desirable magnitudes necessary to force the thrust block 86' toward the gear peripheries, without destroying the fluid

film between teeth ends and the thrust block surfaces 120 and 122.

The discharge pressure passage 129 (FIGURES 2 and 9) provided through the thrust block 86 extends from pressure face 124 to outlet face 128. The inlet opening of passage 129 can extend substantially the entire width of the thrust block 86 and constitutes an elongated slot like aperture 127. Passage 129 is shaped to form a transition of approximately constant cross-sectional area from the inlet slot to a centrally located circular outlet 131 at the rear face of the thrust block 86. The fluid under pressure leaving thrust block 86 has a flow path substantially coextensive with the pump casing outlet 136.

Referring to FIGURE 1, the support casing 98 has a gear cavity 146, providing substantial clearance around the intermeshed gears 82 and 84, and an inlet passage 148 which communicates through the casing wall to the cavity 146. Inlet fluid will thus be available through approximately 270° or 70 percent of the peripheries and sides of both gears 82 and 84 thus essentially assuring that all gear teeth will be filled with and carry a full load of inlet fluid when they pass into sealing engagement with the arcuate surfaces 120 and 122 of thrust block 86, and the sealing surfaces of seal plates 88 and 90.

The seal plate area seals 94 and 96 are disposed in recesses 150 formed in the casing structure end plates 102 and 104 and lie within the area defined by the peripheries of seal plates 88 and 90. Seals 94 and 96 define the area in which pump discharge pressure, plus resilience of the seals, may act to force seal plates 88 and 90 into a sealing relationship with the faces of the gears 82 and 84 and the thrust block 86. There is an accurately controlled pressure force between the seal plates and the gear faces as well as between the thrust block and the peripheries of the gears and this accurately controlled force may be defined as being sufficiently high in value to squeeze the oil film between the wear plates and the side faces of the gears and the thrust block to such a low value of thickness that leakage between the sealing faces is at a minimum, yet not high enough in value so that the oil film is ruptured which would result in galling between the inner face surfaces of the wear plates 88 and 90 and the side faces of gears 82 and 84. This low value of film thickness is a desired "optimum clearance" and can also be defined as the least amount of clearance that can be tolerated from a lubrication standpoint and, therefore, the least clearance leakage that will result from pumping against a high discharge pressure.

Annular seal plate seals are resilient and have a cross-sectional thickness greater than the depth of recesses 150. In the assembled pump the seal plates compress the annular seal plate seals a slight amount resulting in a mechanical bias urging the seal plates toward the side faces of the gears and the thrust block.

By the use of pressure controlled forces between limited area contact members (the thrust block 86 and seal plates 88 and 90), the pump gears are pressure sealed in a definitive manner over a specific desired area which can be held to a minimum value. In contrast to a conventional fixed clearance gear tooth pump 20 which effects a pressure gradient seal over a large area, the present invention provides a fixed, essentially constant clearance seal over a small area.

It will be clearly apparent that pumping action of the pump of this invention is not dependent upon the presence of a pump casing or closely fitting end plates as in the aforementioned fixed clearance gear tooth pump 20. Pumping action can be obtained with the pump components of the present invention without the necessity of an enclosing pump casing and end plates. This latter aspect is represented in FIGURE 8 where the casing is replaced by a skeleton support structure 152 which is necessary to journal the gears, provide a holding means for the thrust block and seal plates and enable a discharge connection. Such a pump can be immersed in the fluid

medium being pumped, the unenclosed gear teeth providing an effective direct pump inlet.

Casing structure 98 and end plates 102 and 104 in pump 80 are required only as support for the gear shaft bearings 110 and 112, to provide inlet and discharge connections, and to maintain the annular and area sealing members 92, 94 and 96 in abutting and overlaying relationship with their respective components. In the majority of installations the casing will provide a physical protection against the danger inherent in rotating gears and efficiently channel the inlet fluid into the teeth on the gear peripheries.

With particular reference to FIGURE 1, the seal plate 88, and the same is true of seal plate 90, is so formed to have a distinct radial clearance from the gear shafts 114 and 116. The seal plate 88 is also dimensioned to be disposed within matching recesses 152 and 153 in the casing structure 98 and end plates 102 and 104 respectively with substantial clearance between its edges and the edges of the recesses 152 and 153, within optimum limits to prevent its moving entirely out of desired position. Having such clearances, seal plates 88 and 90 will have complete freedom to "float" within optimum limits, the edges of recesses 152 and 153 keeping the seal plates from moving outside of the area for which sealing is desired. Actual construction of the seal plates need not necessarily be the particular construction shown in FIGURES 1, 2 and 3 but should utilize the "floating" principle. The term "floating" used herein, and in the claims, in connection with the pump discharge seal components, i.e., the seal plates and the thrust block, is intended to mean that such components may bodily shift their positions in more than one path relative to each other and to the pump gears, at least one of such paths being directed toward and away from the pump gears.

The area of seal plates 88 and 92 encompassed within the confines of area seal 94 and placed under discharge pressure is an area which is selectively defined to produce a uniform loading between portions of the inner faces of seal plates 88 and 90 and the overlapped side faces of gears 82 and 84 and side faces of thrust block 86. By making such loading essentially uniform, the wear on the seal plates due to the rotation of the gears will be reduced to a minimum yet the sealing coaction between seal plates and gears can be maintained at the same degree of efficiency as the sealing coaction between the seal plates and thrust block.

Operation

In FIGURE 1, fluid will enter the inlet 148 and pass into the gear recess cavity 146. Because 75% of the periphery of the pump gears 82 and 84 as well as approximately 70% of their side face areas are not confined in close critical relationship to the casing or the end plates, the inlet fluid which is at relatively low pressure at 146 can enter the gear tooth cavities at many positions over an extensive area and at a relatively low flow rate which permits pump operation in the direction of the arrows (FIGURE 1) at shaft speeds many times higher than conventional fixed clearance gear tooth pumps. The rotating gears pick up the inlet fluid in the spaces between teeth and carry such fluid toward the intermeshing gear position G. Progressing toward point G, the end faces of the gear teeth cooperate with a minute fluid film to provide a seal against the arcuate surfaces 120 and 122 of the thrust block 86. Trapped fluid between gear teeth cannot pass position G and cannot flow back past the arcuate seal surfaces of the thrust block 86, hence the volume of fluid in zone 126 is placed under pressure and passes through the thrust block passage 129 toward and through casing outlet 136.

Fluid under pressure exists throughout the zone 126 and in variable areas of each of the arcuate surfaces 120 and 122 depending on gear tooth position along the surfaces. The same discharge pressure exists on the outlet

face 128 of thrust block 86. Due to the differential area accurately designed between the front and rear faces of the thrust block, the pressure differential forces urge the thrust block 86 toward the gear peripheries, this differential pressure being sufficient to squeeze the liquid between the arcuate thrust block surfaces 120 and 122 and the end faces of the gear teeth to a very thin film with a minute thickness value, yet not high enough to rupture the liquid film. The most efficient fluid seal is thus provided.

Pressure on fluid in pressure zone 126 will also communicate through the seal plate passages 134 to the outer seal plate pressure areas defined by the area seals 94 to thus provide the controlled differential pressure loading on the seal plates resulting in a uniform loading between the inner faces of the seal plates 88 and 90 and the side faces of the gears 82 and 84 and the side faces of the thrust block 86.

Since only a very small portion of the periphery of the pump gears 82 and 84, that portion of the gears between points G and H in FIGURE 1, is subjected to any gradient of discharge pressure, the bearing loads which result from the unbalance between the discharge pressure and the inlet pressure are substantially less than those which occur in a fixed clearance gear tooth pump. These bearing loads will be approximately 60% of the bearing loads in an equivalent size conventional pump, when the two pumps are operated at similar capacity and pressure.

For a given size pump gear (i.e. a gear with specific outside diameter and tooth-pitch) there is a resulting maximum shaft diameter, which in turn fixes the maximum bearing size and capacity used on such gear. Since the projected area of such gear (subject to pressure) is fixed by construction and the bearing load capacity is fixed, it follows that the maximum unit pressure (hydraulic) under which a given pump is to be operated is also fixed.

Referring to FIGURE 9, it is immediately apparent that, since the projected area of the gears (which is subjected to discharge pressure) is definitely limited by the action of the thrust block and seal plates, a higher unit discharge pressure can be tolerated before the maximum allowable bearing load is reached, than will be possible in conventional pumps as in FIGURES 5 and 6. Conversely, for equal discharge pressures, the bearing loads will be but 60% or so of that of a conventional fixed-clearance pump.

Again referring to FIGURE 9, the very much reduced areas over which the discharge pressure can act (in all 3 planes) materially reduces the weight of the cast pump casing and end-plates. Additionally, the bolts which are normally used to fasten the end-plates to the pump-casing can be a much smaller size.

The use of limited small areas of contact between the inner-faces of the seal plates and the side faces of the gears as well as between the thrust block and the peripheral surfaces of two gear teeth permits definitive sealing to be accomplished with the least amount of mechanical power (input shaft torque) loss.

By comparison pump mechanisms, exemplified by the United States patent disclosures of Lauck 2,527,941; Wichorek 2,691,945 and Lindberg 2,728,301, have seal plate surfaces in contact with 100% of the side surfaces of the pump gears. As a result, pumps of such construction show mechanical efficiencies in the order of 65% to 75%. In contrast to this, pumps using the principles of this invention have been demonstrated to have mechanical efficiencies in the order of 95%.

To achieve the necessary working clearances in an assembled pump of the conventional, fixed-clearance type (as previously described) there are at least 22 dimensions, on component parts, which must be held within very close manufacturing limits. This number is reduced to 11 on the pump of this invention and may possibly be reduced still further.

The controlled clearances, which are required for the optimum performance of the pump of this invention, are achieved by the abutting and overlaying relationship of the vital components when under the influence of controlled forces, which forces are derived from and are proportional to the discharge or working pressure of the pump. Thus, these clearances are the result of component arrangement and fluid pressure forces and are not created by the painstaking and accurate fitting of components (one with respect to the other) necessary in conventional fixed clearance gear pumps.

For various modifications of the principles of this invention, reference will be had to FIGURES 10, 12-14 and 16-20. In FIGURE 10 the combination of thrust block and seal plates is illustrated in an exploded perspective. The seal plate 88 is illustrated with the afore-described high pressure passage 134 which diverts fluid from the pressure zone 126. However such fluid pressure passage can be relocated as in the seal plate 90' (FIGURE 10) which incorporates a passage 134' disposed adjacent an area of the thrust block 86' and co-extensive with a fluid passage 156 formed through the side wall of thrust block 86'. This is merely a different manner of providing fluid communication from the high pressure fluid to the area defined by the area seal 94.

Unloading modification

The pump of this invention is ideal for use in a circuit where unloading of the pump is desired, such a circuit being illustrated in FIGURE 13. In unloading service, it is desirable to cause the pump 180 to cease delivering pressure fluid after a certain work cycle has been accomplished. This is desired to conserve power and to avoid undue heating of the pumping fluid. One such example of an unloading system is in the use of a pump to power a hydraulic molding press 181 where fluid power is required for a few seconds to close the press but no fluid power is required while the press is held closed, for example, during a curing cycle of the work article being subjected to the press pressure.

To utilize the pump 180 for such unloading operation, all components of the illustrated example may be essentially identical with that described for the pump embodiment 80 disclosed in FIGURES 1, 2 and 3 however in lieu of the relatively large fluid passages 134 through seal plates 88 and 90, orifice passages 182 are provided in seal plates 188 and 190 between the outlet pressure chamber and the area defined by area seals 194. It is to be clearly understood that this unloading modification is equally applicable to pumps using any form of thrust block assembly such as the first, second and third alternate embodiments hereinafter described, and others contemplated within the concepts of this invention. The pump outlet is connected to a line 196, which includes check valve 198 and connects to the pressure cylinder 200 of hydraulic press 181. A by-pass line 202, which includes a control valve 204, connects between line 196 and a fluid reservoir (not shown).

Tapped openings 206 and 208 in the pump end plates communicate with the area defined by area seals 194 and enable conduit connections for lines 210 and 212 which join in line 214 communicating through a control valve 215 into the fluid reservoir.

To initiate system operation, both of the control valves 204 and 215 would be closed and pump discharge pressure, communicating through the orifices 182, would be present on the outer surfaces of seal plates 188 and 190 in the areas defined by the seal plate seals 194. Under this condition pump discharge at full pressure would be present in line 196 to be introduced in the pressure cylinder 200. When the press 181 is fully closed and full pressure is trapped in the press cylinder by the line check valve 198 the control valve 215 may be opened to drain into the fluid reservoir.

Differential pressure thus created across the small

orifice 182 by a high volume drainage flow through valve 215 will lift the seal plates 188 and 190 away from the gear faces against the compression action of area seals 194. When this condition exists, no fluid can be discharged through the pump discharge port because pumping action is nullified by lifting of the wear plates. Fluid is by-passed and can then only circulate with the gears within the pump casing.

When the control valve 215 is again closed, pressures on both sides of the seal plates will equalize and the compression of the area seals 194 (or a separate independent spring member not shown) will force the seal plates into sealing engagement against the gear side faces and the side faces of the thrust block, permitting differential sealing forces on the seal plates to provide self-compensating high pressure sealing and pumping action is again initiated.

In connection with the use of this mechanism as a hydraulic motor, it should be noted that a motor delivers power as a result of unbalance of forces about the gear shaft centers. Even though the hydraulic forces of the conventional fixed clearance pump as shown in FIGURES 5 and 6 are very high the unbalance about the gear shaft centers is not high. In the improved pump of this invention the hydraulic forces are lower on the individual gear members but at the same time they are unbalanced to a very high degree due to the fact that the hydraulic forces are localized through the coating surfaces of the thrust block and gear teeth. This unbalance is what leads to a greatly increased torque output characteristic which will be present even at low shaft speeds in the present invention where the efficiency of the conventional fixed clearance gear teeth motors drops off considerably, even to the point where the motor becomes inoperative.

First alternate form of pressure seal

A further alternate construction 220, illustrated in FIGURE 12, has a split thrust block 221 consisting of two similar blocks 222 and 224 resiliently biased away from each other by means such as a coil spring 226 disposed in seats 228. Such an installation permits use of smaller areas on the thrust block under discharge pressure influence and permits separate floating and self-aligning of the cooperating surfaces between each gear and its associated half of the thrust block assembly.

A variation of the split block embodiment is accomplished by removing a portion of the casing structure adjacent the rear portion of each thrust block half as indicated by recess 230 (FIGURE 12). In effect this arrangement provides a small elongate abutment area 232, the width of which can be minimized by beveling the corners 234, which will act as a hinge line enabling self-adjustment of the thrust block half for closer coaction between the thrust block arcuate surfaces and the end faces of the gear teeth. It is to be understood that a resultant component of fluid pressures acting upon the faces of the gear block segment 212 will be directed toward the gears and thus force the gear block segment against the gear teeth.

To obtain stability of the split blocks against the gear teeth end surfaces, the arcuate contours 236 should be of sufficient length to always be in contact with at least two teeth end faces regardless of the form of gear and tooth being used. The relationship of thrust block areas subjected to discharge pressure can be so designed that a higher unit pressure will be exerted by the thrust block seal portions against the gear teeth as they first come into sealing engagement with the block 212 than the unit pressure exerted against the teeth as they leave sealing engagement with block 212. This relationship can be correlated with the oil film thickness versus unit pressure relationship, hereinafter discussed, so that an initial sealing pressure and engagement occurs between gears and thrust block assembly immediately adjacent the pressure dis-

charge zone and a sealing engagement under higher pressure occurs near the gear tooth entrance portions of the thrust block arcuate surfaces. This relationship will lead to a more efficient seal because the hydraulic force tending to disrupt the seal near the entrance portion of the thrust block arcuate surfaces would be greatly reduced and yet would be attempting to force a liquid film through a clearance of minimum value.

Second alternate form of pressure seal

The pump embodiment 250 illustrated in FIGURES 16, 17 and 18 utilizes a full floating pressure discharge sealing means in accord with the concepts of this invention, the primary difference being in the use of two thrust block halves 252 which include a direct thrust block to pump body cooperation enabling the omission of a separate area seal member.

As shown in FIGURES 16 and 17, pump 250 has a body 254 with end covers 255, inlet 256, gear cavity 258, gears 260 and seal plates 262 similar to those described in connection with the pump in FIGURES 1, 2 and 3. For clarity, the seal plate annular resilient seals are not shown and the seal plate 262 in FIGURE 16 is shown in phantom lines.

Each side of pump body 254 is recessed at 264 adjacent the discharge side face 266 of gear cavity 258, the discharge side face 266, as illustrated being planar and parallel to a plane through the axes of gears 260. In this embodiment, the reduced pump body portion 268 between the recesses has a critical thickness which is the same dimension as the width of the pumping gears.

Two thrust block halves 252 of similar tapering shape are disposed in sliding relation between the face 266 of reduced body portion 268 and the peripheries of gears 260. Compression coil springs 270 or other suitable expandable elastic devices, seated in opposed sockets 272 in the inner faces 274 of the thrust block halves 252, maintain the two halves in an initial cooperative relationship between gears 260 and body 254. The major extent of the contoured face 276 of each thrust block half 252 (FIGURE 18) is curved with a radius essentially equal to that of gear 260 and the opposite face 278 is flat so each block half 252 fits in the manner of a wedge between the flat body face 266 and one gear 260 with the flat block face 278 against the body face 266 and the contoured block face 276 against the gear tooth periphery portions. A small portion of contoured face 276 at the narrow end of each thrust block half 252 is relieved by a short surface 280 (FIGURE 18), parallel to the flat face 278, permitting unobstructed gear tooth entry to the contoured face 276 of each thrust block half 252.

The thrust block halves 252 have a width dimension equal to that of the gears 260 and the reduced width body portion 268. The seal plates 262 are disposed in a planar sealed relationship over the side faces of the gears 260, the thrust block halves 252 and reduced body portion 268 and are maintained in such relationship in a manner as described hereinbefore with respect to FIGURES 1, 2 and 3.

Pumped fluid enters the body inlet 256, is picked up by the gear teeth around the major portion of the periphery of gear cavity 258 and carried into the discharge pressure cavity formed between the gears 260, thrust block halves 252 and seal plates 262. From the discharge pressure cavity, fluid under pressure passes between the thrust block halves 252 and through a pump body outlet passage 284 to a suitable discharge pressure connection (not shown).

Viewing FIGURE 18, the arrows directed toward faces 274 and 276 of thrust block half 252 represent components of fluid pressure acting on thrust block half 252 in a direction parallel to the discharge face 266 of the body cavity 258. The force acting on thrust block face 274 is discharge fluid pressure whereas some of the opposed components of force acting on contoured face 276 are discharge pressures and some are fractions of discharge pres-

sure, depending upon the position of the contacting gear teeth and the effective fluid seal between gear teeth and the contoured face 276. It is clear, from an analysis of the components of force represented in FIGURE 18 that the unbalance of forces (resultant R in FIGURE 18) tending to force the halves 252 against the gear teeth, can be controlled to a small value. The major components of force developed by the fluid under pressure on each thrust block half 252 will be acting to bias the thrust block halves 252 against the discharge face 266 of the body cavity 258 and are utilized to provide a direct contact seal (metal to metal if the thrust blocks and casing are both made of metal) at plane A (FIGURE 18) thereby obviating the need for the annular lip type seal member 92 of FIGURES 1, 2 and 3. The desired resultant force R is designed to provide, as close as possible, a minimum thickness fluid film seal between the contoured faces 276 of thrust block halves 252 and the gear teeth.

Third alternate form of pressure seal

FIGURES 19 and 20 illustrates a third alternative form of the discharge thrust block pressure seal in a pump 300, in which the floating thrust block 302 and the means providing its annular seal with the pump casing are combined in a unitary flexural member. In other aspects, this embodiment is similar to that disclosed in FIGURES 1, 2 and 3.

Although the illustrated pump body 304 with its inlet 306 and discharge fitting 308 are fabricated from several components, if desired, it could be made integral with two end plates as in FIGURES 1, 2 and 3. The two part pump body 304, with the main portion 310, containing the gear cavity 312, and the auxiliary side plate 314, fastened to the discharge side of body portion 310 by pump body end plates and bolts 315, enables ease of assembly of the thrust block 302 and firmly positions the end portions 316 of thrust block 302 against shoulders 317 in the major body portion 310 for a purpose to be later described. The discharge fitting 308 is threaded into a sleeve gland 318, and has a spigot portion 320 which projects through the sleeve gland. An annular recess 322 in the face of sleeve gland 318 surrounding the spigot 320 receives an O-ring seal 324 of suitable resilient material such as "Teflon." Sleeve gland 318 is fastened to the pump body side plate 314 by screws 326 with the discharge fitting spigot 320 disposed in a discharge opening 328 of a discharge passage through the pump body side plate 314. In assembly, the O-ring 324 is compressed to a high pressure fluid tight seal between the discharge fitting 308, sleeve gland 318 and pump body side plate 314.

Seal and wear plates 330 (FIGURE 20) are essentially identical to those illustrated in FIGURES 1, 2 and 3, floatingly overlying a portion of the side faces of gears 332 adjacent the discharge portion of the gears, and the major extent of side faces of the unitary thrust block 302. Of course in all embodiments the seal plates utilize some form of upper resilient seal member as 94 in FIGURE 1 and have a pressure equalizing passage as 134 in FIGURE 1 connecting both sides of the plate.

Flexural thrust block member 302 is restrained between pump body members 310 and 314 for accurate positioning, is made of a wear resistant, yet flexible, material such as "Micarta," "nylon," "Teflon," etc., has a width the same as the width of pump gears 332, and is hollow with an annular sealing lip 334 engaging the inner face 336 of pump body side plate 314. The face 338 of thrust block 302 which faces the interior of pump body 304 is contoured to be in reasonably close proximity to the tips or periphery of the gear teeth when the pump has zero discharge pressure.

As pump discharge pressure increases, the pumped fluid passes through a passage 340 in the central portion of thrust block 302 enabling fluid discharge communication through pump body side plate 314 and discharge fitting 308. Fluid under discharge pressure acts on all interior surfaces of the hollow flexural thrust block 302 forcing

the sealing lips 334 into a high pressure seal against side plate face 336 and preventing high pressure fluid from escaping from between the thrust block and pump body.

Under pumped fluid discharge pressure, as denoted by the arrows in FIGURE 19, on portions of contoured thrust block face 338 and against the greater area of the opposed inside thrust block surface 342, a differential force R_1 (FIGURE 19) is created on the thrust block wall 344 inducing bending in flexural thrust block member 302 from its ends 316 which engage the pump body shoulders 317. The deflection of thrust block wall 344 due to a bending moment $R_1 \times M$ (where M , FIGURE 19, is the distance between R_1 and the outer edge of the inner thrust block face 342) results in varying degrees of deflection due to the tapered cross section of thrust block wall 344 and such deflection will be highest adjacent the discharge opening 340. This deflection closes down the gap between gear peripheries and the contoured face 338 of the thrust block 302 as discharge pressures increase, thereby reducing leakage past the tips of the gear teeth.

It is obvious that, by skillful and careful incorporation of design dimensions, the physical proportions of thrust block member 302 can be so determined as to maintain a constant minimum fluid sealing leakage (irrespective of discharge pressure) past the gear tooth tips. This condition will be ideal for low wear and long life.

It was previously pointed out that a discussion would be presented concerning relationships between the fluid flow and the clearance existing between two relatively moving components in which that clearance is used to effect a fluid seal and where actual contact of the relatively moving components is not desired.

It is known that for a given pressure differential across a slot that the volume of fluid flow will vary in proportion to the cube of the clearance. Therefore, the smaller the dimension of critical clearance or slot width which can be obtained without causing a rupture of the sealing fluid film the more positive sealing effect will result. A relationship exists between the unit pressures on two relatively moving components tending to force those components into actual engagement and the dimension of fluid film thickness between the two components. This relationship can be determined by laboratory test equipment and carefully correlated to the type of fluid being used to obtain the fluid seal between the relatively moving parts. In furtherance of this belief, experimentation is being carried out to determine the relationship between thicknesses of various fluid films and the unit pressures applied thereon from some value close to a 0 differential pressure up to a value at which the film is ruptured. Presently available information indicates that the relationship of film thickness to unit pressure will approximate the curve shown in FIGURE 15 in which the film thickness rapidly decreases to a leveling off position and at some finite value indicated by the point P of the curve will abruptly break and be disrupted. In accordance with such theory, a range of unit pressures, for example the approximately level portion R of FIGURE 15, can be determined for a specific fluid being pumped within which the resultant fluid film thickness will be essentially at the minimum value which can be obtained prior to the point of rupture. Utilizing this knowledge the design differential areas enabling a biasing hydraulic pressure to act on the thrust block of this invention can be accurately controlled in accord with specific conditions of pump use, such as type of fluid and working pressure ranges, to provide this minimum thickness of fluid between the end faces of the gear teeth and the arcuate thrust block surfaces 120 and 122 under pressures well below that required to rupture the film and to provide the most effective fluid seal at those points. This same knowledge can be utilized in designing the differential pressure areas of the seal plates to thus obtain a safe unit pressure which nevertheless enables the desired minimum thickness of fluid film between the seal plates and the side faces of the

gears and the side faces of the thrust block. The type of optimum clearance pump herein before disclosed enables utilization of such knowledge to obtain a much higher efficiency gear tooth pump than any heretofore proposed.

The foregoing description and drawings disclose various constructions and principles of operation for a self compensating optimum clearance gear tooth type pump in which enmeshed gears are disposed with a sealed coaction against a floating thrust block, and two floating side seal and wear plates are disposed with sealed coaction against the pumping gears and thrust block. The pump casing and casing end plates are used to provide bearing support for the gears and back-up support for the floating thrust block and the seal and wear plates and are not used to provide any direct sealing cooperation with the gears, hence no critical clearances between casing and pumping seal surfaces of relatively moving components are required. By utilizing floating thrust blocks and floating seal and wear plates having sealed differential areas in communication with discharge fluid under pressure, a controlled force biasing the floating components into close fluid sealing engagement with portions of the pumping gears, is obtained. An adaptation of the floating seal and wear plates to control pumping output by selective relief of wear seal and plate biasing force is enabled by providing orifice bleeds through the seal and wear plates.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. A tooth-gear pump with self-energizing pump surface sealing including: discharge fluid actuated, shiftably, gear periphery sealing means; two separate spaced apart discharge fluid actuated, floating, gear side surface sealing means in sealed combination with said gear periphery sealing means; and means mounting the tooth-gears, said periphery sealing means and said two side surface sealing means for independent shifting of each of said three sealing means and independent floating disposition of at least said two side surface sealing means relative to said periphery sealing means and the tooth-gears.

2. A gear pump comprising: support structure, meshed gears journalled in said support structure; outlet thrust block means, contoured to fit in fluid sealed engagement against adjacent end faces of the teeth of said gears, floatingly shiftably mounted in said support structure; and seal means floatingly shiftably disposed in said support structure on each side of said meshed gears and thrust block means sealingly engaging adjacent surfaces of said gears and block means; said thrust block means and said seal means on each side being shiftable independently of each other.

3. A gear pump comprising: support structure; meshed gears journalled in said support structure; outlet thrust block means contoured to fit in fluid sealed engagement against adjacent end faces of the teeth of said gears and floatingly shiftably mounted in said support structure; means between said support structure and said outlet thrust block means to provide a bias force tending to urge said thrust block means against said gear end faces; seal means floatingly shiftably disposed in said support structure on each side of said meshed gears and thrust block means sealingly engaging adjacent surfaces of said gears and said thrust block means; said thrust block means and said seal means on each side being shiftable independently of each other; and means between each seal means and said support structure to provide a bias force tending to urge said seal means against the gears and said thrust block means.

4. A gear pump comprising: support structure; meshed gears of equal thickness journalled in said support structure; pump outlet thrust block means having side faces, a thickness equal to that of said gears, and contoured to fit and shiftably mounted in said support structure between and adjacent the end faces of teeth of said gears with said thrust block means side faces coplanar with the side faces of said gears; means between said support structure and said outlet thrust block means to provide a bias force tending to urge said thrust block means against gear teeth end faces; seal means floatingly, shiftably disposed in said support structure adjacent each side of said meshed gears and of said thrust block means sealingly cooperating with adjacent surfaces of said gears and thrust block means to provide a discharge pumping cavity; said thrust block means and said seal means on each side being shiftable independently of each other; and means between each seal means and said support structure to provide a bias force tending to urge said seal means evenly toward the gear side faces and the side faces of said thrust block means.

5. A gear tooth pump with self compensating optimum pumping sealing clearances comprising: a support structure; enmeshed toothed pump gears journalled for rotation in said pump structure; discharge thrust block means maintained by said support structure in shiftable disposition generally between said pump gears adjacent their meshed teeth; means to exert a force on said discharge thrust block means tending to urge said thrust block means toward the end faces of the teeth of said pump gears; sealing wear plates floatingly shiftably disposed on each side of said pump gears and said thrust block means and, in conjunction with pumped fluid, to provide a fluid seal overlying the pumping portion of said gears and the space between the thrust block means and said gears; said thrust block means and each of said sealing wear plates being separate components; and means to create a differential fluid pressure on each of said sealing wear plates tending to bias them toward said gears and thrust block means.

6. A meshed gear tooth pump comprising: a full floating discharge zone sealing assembly having first means with a discharge passage therethrough and opposed differential areas subject to pumped fluid under discharge pressure maintaining said first means in self-compensated pressure sealing engagement with teeth faces of the gears adjacent the meshed tooth discharge zone, and second and third means structurally separate from each other and from said first means and floatingly shiftably disposed respectively on opposite sides of the gears adjacent the meshed tooth discharge zone, each of said second and third means including opposed differential areas subject to pumped fluid under discharge pressure maintaining each of said second and third means independently in self-compensated pressure sealing engagement with said respective sides of the gears and with said first means to provide a meshed gear discharge chamber between the gears and said discharge passage, and each of said first, second and third means being independently shiftable relative to each other.

7. A meshed gear tooth pump as defined in claim 6, wherein at least one of said second and third means include an orifice bleed between their said opposed differential areas and a selectively operable controllable fluid pressure relief means is provided in fluid communication with the meshed tooth discharge zone through said orifice bleed.

8. A meshed gear tooth pump as defined in claim 6, wherein the meshed pump gears are equal in width; said first means includes a thrust block means, contoured to sealingly engage the teeth end faces of the gears adjacent their meshing position, having a width equal to the width of said gears; and each of said second and third means includes a seal plate in fluid sealed engagement with said gear side faces and said thrust block means with a fluid

passage through each plate from the meshed tooth discharge zone.

9. A meshed gear tooth pump as defined in claim 8, wherein means including an annular resilient seal provide a fluid tight variable volume chamber on the sides of each seal plate opposite the meshed tooth discharge zone, said fluid passage through at least one of said seal plates comprises a fluid balancing bleed, and a selectively operable fluid pressure controlled relief means is in fluid communication with said fluid tight variable volume chamber of at least said one of said seal plates.

10. A meshed tooth pump as defined in claim 8, wherein said thrust block means constitutes at least two parts each of which is contoured to sealingly engage the faces of one of said pump gears adjacent the pump gear meshing position.

11. A meshed gear tooth pump as defined in claim 6 wherein the pump includes a casing structure journaling the pump gears, providing sealed support for said sealing assembly and having non-critical relative large clearances from gear surfaces particularly adjacent the gear teeth.

12. A meshed gear tooth pump as defined in claim 11, wherein the sealed support provided by said casing structure for said sealing assembly provides an isolated pump inlet chamber and outlet chamber and said casing structure has an inlet and discharge respectively leading to said inlet and outlet chamber.

13. A meshed gear tooth pump as defined in claim 12, wherein the inlet chamber encompasses approximately seventy percent of each of the pump gears.

14. A gear tooth pump which has a casing support structure for intermeshing pumping gears with non-critical clearances between the casing support structure and the gear side faces and teeth peripheral faces, a thrust block shiftably mounted in said support structure and engaging a minimum portion of the gear peripheral faces, and two seal plates structurally separate from each other and from said thrust block and floatingly shiftably mounted in said support structure overlapping said gear side faces and said thrust block and each of which is sealingly biased by discharge fluid from the wall of said casing into engagement with the gear side faces and the thrust block.

15. A gear tooth pump as defined in claim 14, wherein said seal plates which sealingly engage portions of the side faces of the gear teeth and the thrust block seal a space between said thrust block and intermeshed gear teeth in fluid communication with the pressure discharge side of the pump gears, and an annular resilient seal structure disposed between each said seal plate and said casing aids in maintaining the seal plate against said gear and said thrust block.

16. A self-compensating gear tooth pump comprising: a support structure which journals the pumping gears in meshed relation; a thrust block shiftably disposed in said support structure, contoured to fit a portion of the peripheries of the pumping gears, having a thickness substantially exactly equal to the thickness of the pumping gears and having a discharge passage extending through said thrust block from the gear side pressure face of said block; a biasing means maintaining said thrust block in sealing engagement with said gears; a discharge pressure area provided on the outlet side of said thrust block pressure passage of sufficiently greater dimension than the effective area of the thrust block pressure face to provide a controlled biasing force on said thrust block; and side seal means overlapping said gear side faces and said thrust block, each side seal means being sealingly biased by discharge fluid from the support structure into engagement with the gear side faces and the thrust block, and each side seal means being floatingly shiftably disposed in said support structure independently of each other and of said thrust block.

17. A self-compensated gear tooth pump as defined in claim 16, wherein said side seal means includes two seal plates overlapping the sides of said thrust block and the faces of the teeth of intermeshed gears adjacent their

discharge to completely cover the pressure discharge space between the intermeshed gears and said thrust block, and a resilient device cooperates between the seal plates and the support structure to bias the seal plates toward engagement with said thrust block and said pumping gears.

18. A self-compensated gear tooth pump as defined in claim 17, wherein said resilient devices are annular seal rings and means provide for passage of pumped fluid under pressure to the area on said seal plate defined by said sealing ring so output pump pressure can be utilized to bias the seal plates toward said thrust block and pumping gears and the biasing force will be automatically compensated for changes in pump output.

19. A self-compensated gear tooth pump as defined in claim 18, wherein said seal plates have an orifice type fluid communication to the pump pressure space and means provide a control outlet from the seal plate sealed area selectively operable to completely relieve fluid pressure from within the seal plates sealed area thus enabling the seal plates to be biased by pump output pressure out of operative sealed engagement with the thrust block and pumping gears to effectively by-pass pump discharge and cause immediate cessation of high pressure pumping output.

20. A meshed gear tooth pump as defined in claim 16 comprising a full floating discharge zone sealing assembly providing self-compensated pressure sealing means in liquid film sealing engagement with teeth faces of the gears adjacent the meshed tooth discharge zone and with opposite sides of the gears adjacent the meshed tooth discharge zone; said self-compensated pressure sealing means including said thrust block means and said side seal means, each of which have opposed differential control areas subjected to pump liquid under discharge pressure and being proportioned to provide a unit pressure differential force on each of such means in a sealing direction within a desired range of unit pressures which when applied to a film of the pump liquid, existing between said thrust block means and said gears and between said side seal means and said gears, provides an approximately minimum thickness film of the pumped fluid and the maximum pressure value in said range being sufficiently lower than the pressure required to rupture the film of liquid to normally assure no rupture of said film during pump operation.

21. A gear pump comprising: support structure; meshed gears journalled in said support structure; outlet thrust block means comprising two tapered half blocks contoured to fit in fluid sealed engagement against adjacent end faces of the teeth of said gears and floatingly shiftably mounted against a surface in said support structure opposite the end faces of said teeth; means between said half blocks to provide an initial bias force tending to wedge said thrust block halves between said gear end faces and said support structure surface; seal means floatingly shiftably disposed in said support structure on each side of said meshed gears and thrust block means sealingly engaging adjacent side surfaces of said gears and said thrust block means; each of said seal means being independently shiftable relative to each other and to said thrust block means; and means between each seal means and said support structure to provide a bias force tending to urge said seal means against the side surfaces of said gears and said thrust block means.

22. A gear pump with self-compensating pump surface sealing comprising: a flexible differential area discharge fluid actuated gear tooth end face sealing and discharge passage means in sealed combination with two floating and spaced apart differential area discharge fluid actuated gear side surface sealing means and support means mounting each of said means for shifting movement relative to and independent of each other.

23. In a gear tooth pump which has a casing support structure for intermeshing pumping gears with non-critical clearances between the casing support structure and the

gear side faces and teeth peripheral faces; a flexible thrust block, with a discharge passage, engaging a minimum portion of the gear peripheral faces and including an annular flexible pump casing sealing lip surrounding the thrust block discharge passage; and two seal plates floatingly shiftably disposed within said casing support structure, overlapping said gear side faces and said thrust block and both seal plates being sealingly biased between the wall of said casing into fluid sealed engagement with the gear side faces and the thrust block; each of said block and said two seal plates being structurally separate components.

24. A self-compensating gear-tooth pump comprising: a casing structure which journals the pumping gears in meshed relation and includes an outlet; a flexible thrust block floatingly shiftably disposed in said casing, contoured to fit a portion of the peripheries of the pumping gears, having a thickness substantially exactly equal to the thickness of the pumping gears, a discharge passage extending through said thrust block from the gear side of said block, an annular flexible sealing lip on the outlet side of said thrust block engaging said casing around said outlet and maintained in sealed disposition against said casing by discharge pressure, and a discharge pressure area provided on the outlet side of said thrust block of sufficiently greater dimension than the effective area of the thrust block pressure face to provide a controlled biasing force deflecting said thrust block into fluid film sealed relationship with the pumping gear teeth; two structurally separate seal plate means floatingly shiftably disposed within said casing structure, overlapping the side faces of said gears and at least the sides of the portion of said thrust block which fits the peripheries of said gears; and means to create a differential fluid pressure on each of said seal plate means tending to urge said seal plate means evenly toward the gear side faces and said thrust block.

5 25. In a gear pump, a casing, a pair of meshed gears journaled in said casing, a fluid inlet for said casing opening to an enlarged fluid pick up space at one side of said gears, an outlet for said casing, and means floatingly shiftably mounted in said casing disposed between and embracing said gears at their other side and extending between said other side of the meshed gears and said outlet closely confining the fluid picked up by said teeth substantially only on the sides and teeth faces of said 10 gears adjacent said outlet and delivering said fluid to said outlet at materially increased pressure; said means in the casing comprising a fluid throat defining means at the discharge side of the meshed gears and at least two side members urged by fluid pressure developed within said 15 casing into running seal engagement with the teeth sides and faces of said gears and the sides of said throat defining means, said throat defining means and each of said side members being structurally separate each from the others.
